UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed May 6, 1918, Serial No. 232,803. Renewed February 19, 1925.

My invention relates to mining machines. It has for its object to provide an improved mining machine provided with improved and simplified feeding and controlling mechanism whereby the machine may be fed relative to its work and controlled as desired. A further object of my invention is to provide an improved mining machine whereby, through improved and simplified mechanism 5 cooperating with said feeding mechanism, the mining machine and its truck may be driven and controlled in an improved manner during transport. A further object of my invention is to provide an improved machine of simple and rugged construction, which may be very cheaply manufactured, and one in which the parts are readily assembled during the process of manufacture and readily accessible whenever it is necessary to remove the parts during service. These and other objects of my invention will, however, hereinafter more fully appear.

In the accompanying drawings I have shown, for purposes of illustration, one embodiment which my invention may assume in practice.

In these drawings,—

Fig. 1 is a side elevation of my improved machine mounted upon a truck.

Fig. 2 is a side elevation of the opposite side of the machine when removed from the truck and equipped with its feeding mechanism.

Fig. 3 is a mainly horizontal sectional view taken on line 3—3 of Fig. 4.

Fig. 4 is a vertical sectional view taken on line 4—4 of Fig. 3.

Fig. 5 is a vertical sectional view taken on line 5—5 of Fig. 4.

Fig. 6 is a vertical sectional view taken on line 6—6 of Fig. 3.

Fig. 7 is a detail sectional view taken on line 7—7 of Fig. 3.

Fig. 8 is a detail view of the removable interlocking end plate of the motor casing.

Fig. 9 is a plan view of the machine removed from the truck and having its feeding mechanism arranged for movement in one direction.

Fig. 10 is a similar plan view showing the

feeding mechanism arranged for movement in the opposite direction.

Fig. 11 is a diagrammatic view showing the machine in its sumping and cutting positions with its feeding mechanism arranged for a cut from left to right. 55

Fig. 12 is a similar view showing the machine in sumping and cutting positions with its feeding mechanism arranged for a cut from right to left. 60

Fig. 13 is a similar view showing a modified arrangement of the connections adapted to be used during sumping.

In this illustrative construction, it will be observed that I have disclosed my invention as embodied in an improved machine of the so-called room and pillar type which is adapted, through the medium of improved feeding and controlling mechanism, to be sumped in under the coal and then fed transversely of the same upon the mine bottom in such a manner as to insert a horizontal cut or kerf in the face. It will also be observed that I have disclosed a machine of the type which is adapted to be propelled by its own power from room to room upon its own truck, the power for driving the truck being derived from the machine in an improved manner and controlled in an improved manner. 65 70 75

In my improved construction, it will be observed that the machine is adapted to slide over the mine bottom upon the usual shoe 1, herein preferably rigidly connected at its edges, as by means of longitudinally disposed upstanding members 2 of U section, to an upper bed plate 3, the several elements cooperating to form a chamber adapted to receive a suitable cutter bar 4 in its front end and having its rear end open and preferably cut away, as at 5 to permit the free discharge of the cuttings. As shown, the two members 1 and 3 are each also rigidly connected to a central longitudinally disposed, upstanding member 6 of I-beam section disposed in a suitable slot in the cutter bar, and these members 1 and 80 85

3 are also provided with suitable oppositely disposed pairs of gibs 7, disposed on opposite sides of the member 6 and forming guides for the inner end of the cutter bar. It will also be observed that the cutter bar 4 is, as usual, 90 95 100

provided with a cutter chain 8 which carries suitable cutter bits 9 and is adapted to be moved around the cutter bar by means of power supplied from a cutter chain driving sprocket 10 located in rear of the rear end of the bar 4 and in front of the open rear end of the chamber formed by the members 1, 2, and 3.

- Disposed above the bed plate 3 and resting thereon, is the means for rotating the chain driving sprocket 10, as well as the means for operating the mechanism whereby the machine is propelled under its own power. Each of these mechanisms, as shown, is driven from a suitable motor disposed longitudinally of the bed frame 3 and carried on the front end thereof. As illustrated, the armature 11 of this motor is provided with a beveled pinion 12 on its rear end, which in turn constantly meshes with a beveled gear 13 journaled near the middle of a transverse stud 14. As shown herein, this stud 14 is, in turn, journaled in a suitable upstanding bearing member 15 and, in order to provide room for gearing hereinafter described, is also disposed at an angle to the horizontal. It will also be observed that, as shown, this stud 14 is adapted to be withdrawn longitudinally, if desired, through either of a plurality of openings 16 in the opposite sides of upstanding longitudinally disposed side members 17 herein in the form of plates, preferably rigidly connected to the members 2 and 3 and enclosing the latter and cooperating with a removable cover plate 18 to form an enclosed machine casing. As shown, the ends of this stud 14 are also supported in suitable brackets 19, suitably attached to the members 17, and provided with removable rings or flanges 20 held in place by suitable bolts 21, the construction being such as to permit the stud to be withdrawn through its bearing members after either set of the members 20, 21, is removed. As illustrated, the beveled gear 13 is also connected, preferably removably, as by means of bolts 22, to a sleeve member 23, rotatable on the stud 14, from which the power for both the cutter chain driving mechanism and the feed and propelling mechanism is derived.
- Of these mechanisms, we will first consider the cutter chain driving mechanism. This mechanism is herein adapted to be operatively connected to or disconnected from the constantly rotating sleeve 23 at will by means of a suitable clutch member 24, herein splined to the sleeve at 25 and provided with teeth 26 adapted to engage with cooperating teeth 27 formed on a smaller beveled gear 28 which, as shown, is preferably rotatable on the stud 14 between one of the bearing members 19 and the sleeve 23. It will also be observed that this member 24 may be reciprocated relative to the sleeve member 23 by means of a clutch controlling member 29 operative from the exterior of the cover plate 18, in such a manner

as to cause the teeth 26 to engage or disengage the teeth 27. Attention is also directed to the fact that the gear 28, whose rotation is thus controlled, constantly meshes with and drives, when desired, a large, horizontally disposed beveled gear 30 which is itself journaled on a vertical stud 31 supported by the shoe 1. As illustrated, both the beveled gear 30 and the stud 31 are also disposed coaxially with and extend through the cutter chain driving sprocket 10, the latter being suitably fixed to the beveled gear, as by means of one or more bolts 32. As in a preferred form of my improved construction, it will also be noted that the upper end of the stud is shown herein to be integrally connected to the member 15, while the lower end of the stud 31 is threaded, as shown at 33, and provided on said threaded portion with an adjustable step member 34, annularly grooved as shown at 35 to provide a seat for the end of a reduced sprocket carrying sleeve 36 formed on the lower end of the gear 30, and held in any desired position of adjustment relative to the stud by a plurality of bolts 37 extending upward through the shoe 1. Attention is also directed to the fact that the bed plate 3 is herein shown to be apertured above the sprocket 10, as shown at 38, to permit the ready insertion or removal, as a unit, of the gear 30 and sprocket 10 through the top of the casing.

We will next consider my improved feeding and propelling mechanism which, as above indicated, is also driven from the rotating sleeve 23. Inasmuch as this mechanism in the form shown herein involves several cooperating mechanisms all driven from a single rotating member connected to the sleeve 23, we will first consider these common power connections. As shown, a pinion 39, preferably formed integral with the sleeve 23, is disposed between the latter and the bearing 15 for the stud 14. This pinion 39 in turn meshes with a larger gear 40 on a second, but horizontally disposed, stud 41, preferably similar in other respects to the stud 14 and herein shown to be supported in suitable brackets 42 carried by the side members 17, in such a manner as to permit its withdrawal when desired through either of a plurality of openings 16 in the latter. As illustrated, the gear 40 is also disposed adjacent to a cooperating smaller gear 43, and each of these elements is rigidly connected to a sleeve member 44, which is in turn rotatable on the stud 41 and provided near one of the brackets 42 with a smaller pinion 45, preferably formed integral with the sleeve. Thus, it will be observed that the two members 43 and 45 are continuously driven from the sleeve 23 through the gears 39, 40, and the sleeve 44, in such a manner that power may be taken from either of these members at different speeds.

Cooperating with these gears 43 and 45 and controlling their connection to the elements hereinafter described and adapted to be driven thereby, is a clutch, herein of the friction disk type and of the same general double construction described in my co-pending application Serial No. 225,774, filed March 30, 1918. As shown, the gear 43 meshes constantly with a slightly larger gear 46 formed on one of the disk carrying members 47 of this clutch, while the gear 45 meshes constantly with a considerably larger gear 48 formed on a similar member 49. As described in that application, it will also be noted that an alternative connection of these members 47 and 49 to an inner rotary sleeve 50 which forms a journal for the member 47 and abuts against the hub of the member 49, is obtained by means of a single longitudinally movable disk compressing member 51 adapted to move longitudinally in opposite directions to compress the disks on cooperating disk carrying members 52, 53, splined to the sleeve 50 at 54, and thus force these disks against the other disks carried by the members 47 and 49 when a single exteriorly located clutch controlling member 55 is suitably operated. Thus, it will be observed that when the member 55 is moved in one direction the gear 43 is connected to the sleeve 50, and that when the member 55 is moved in the opposite direction the gear 45 is connected to said sleeve, while both gears are disconnected when the member 55 is in its central or initial position.

Operatively connected to the sleeve 50, through connections hereinafter described, is a feed and truck driving shaft. As shown, the friction clutch mechanism above described is supported on and the sleeve 50 is journaled on a transverse horizontally disposed shaft 56 disposed in rear of and parallel to the stud 41. As shown herein, this shaft is also journaled in and adapted to be withdrawn longitudinally through suitable bearings 57, preferably formed integral with the brackets 42, and has its opposite ends extending through openings 58 and 59 in the side members 17. It will also be noted that one end of this shaft 56 has keyed thereto at 60 a sleeve 61, to which is operatively connected, as hereinafter described, a laterally extending truck driving sprocket 62, while the opposite end of this shaft has keyed thereto at 63 a laterally extending oppositely disposed, feed operating member, herein in the form of a feed chain driving sprocket 64 having a sleeve 65 of similar conformation to the sleeve 61 so that the two sleeves and the elements carried thereby may be transposed when desired.

The mechanism adapted operatively to connect the sleeve 50 and the shaft 56 preferably assumes the form of a variable speed transmission mechanism which will now be

described. Upon the inner end of the sleeve 50 I have shown a small pinion 66, preferably formed integral with the sleeve and meshing with a larger gear 67 fixed to the inner end of a short stub shaft 68 which is journaled in a bearing 69 carried by the bed frame 3. This shaft 68 also has fixed to its opposite end a smaller gear 70 meshing with a larger gear 71 fixed to and rotatable with a rotatable sleeve 72 carried on the stud 41 and disposed between the sleeve 44 and one of the bearings 42. As shown, this sleeve 72 also carries a smaller pinion 73 which in turn meshes with a larger gear 74 rotatably mounted on the shaft 56. Obviously, by providing a suitable clutch mechanism between the sleeve 50 and the shaft 56, and between the gear 74 and the shaft 56, the rotation of that shaft may be controlled, the same being thereby adapted to be driven at different speeds in opposite directions. More specifically, it will be noted that I have provided a clutch member 75 splined at 76 to the shaft 56 and operable by exteriorly located controlling mechanism including a controlling member 77. As shown, this member 75 has teeth 78 on one of its ends engageable with teeth 79 on the sleeve 50, and has other teeth 80 on its opposite end engageable with teeth 81 on the hub of the gear 74. Thus, it will be observed that by connecting the teeth 78, 79, the shaft 56 may be rotated relatively rapidly in one direction, while by connecting the teeth 80, 81, the same may be rotated relatively slowly in the opposite direction.

Referring now to the operative connections adapted to cooperate with the power shaft 56 in feeding the machine and propelling the same when it is mounted upon its truck, we will first consider those elements cooperating with this shaft in feeding the machine when the latter is removed from its truck. Here it will of course be evident that my improved feeding and truck driving mechanism, or either of the same, may be utilized in connection with any well known type of flexible feeding connections adapted to use in room and pillar practice. In this embodiment of my invention I have, however, for purposes of illustration, shown the machine as adapted to be fed by a single flexible feeding member, herein in the form of a chain 82. This member, as is usual in machines of this character, is adapted to have one of its ends fixed to the rib at a point adjacent the face, as for instance to a jack 83, and to be extended backward and around the rear end of the machine, its opposite end being attached at the opposite rib, as for instance to a take-up 84. It will be noted that I have herein provided a guide sheave or idler 85 at the front end of the machine, and that I have in my improved construction also provided other cooperating guiding means adjacent the member 64 and herein

including a plurality of guide sheaves or idlers 86 and 87, herein located above and below the chain driving sprocket 64 and slightly in front of the same, so that by a simple transposition of the chain, the latter 5 may be either brought back over the sprocket 64 and over and under the idler 87, as shown in dotted lines in Fig. 2, to drive the machine in one direction, or be brought back under the sprocket 64 and under and over the idler 10 86, as shown in full lines in that figure to drive the machine in the opposite direction. Obviously, when the idler connections are 15 identic, as herein, only one idler may be provided and adjusted when desired into either of the two operative positions. To cooperate 20 with the chain when the same is disposed in either of these relations, it will also be observed that I have provided a plurality of idlers 88 and 89 at each of the rear corners 25 of the frame, the same preferably being angularly disposed, as shown in Figs. 1 and 2, in order to direct the chain through substantially the same path no matter how it is connected.

It will also be evident that by providing the transposable feed driving sprocket 64 and truck driving sleeve 61, and, preferably though not necessarily, by likewise making the idlers 30 86 and 87 transposable, these elements may be placed at will upon either side of the machine, in such a manner as to enable the machine to act as a right or left hand machine. More specifically, it will be noted that in order 35 to facilitate this transposition, the sprocket 64 is held in place by a suitable bolt 90 threaded in the end of the shaft 56 and readily removable, while the truck driving sprocket 62 and its sleeve 61 are similarly held in place by a flanged bolt 91. As for the 40 idlers 86 and 87, it will be noted that these elements are attached to the side members 17 by means of removable bolts 92 and 93, suitable holes 92' and 93' (Fig. 1) for said bolts being drilled in each member 17. Thus, by simply 45 changing the arrangement of the chain and means cooperating therewith the machine may be made to feed in opposite directions when operating as either a right hand or left hand machine. It will, of course, be understood 50 that when the feed and idler sprockets are so transposed, as from the position shown in Fig. 3 to the opposite side of the machine, it will then be necessary to provide a supplemental idler 94 corresponding to the idler 55 85 or, as is well known in the art, to mount the idler 85 detachably upon the frame so that it also may be transposed. It will also be observed that when cutting in either 60 direction across the face the feed is accomplished by feed operating means on the advance side of the machine and that during 65 sumping at the right and left hand ribs preparatory, respectively, to right to left and 70 left to right hand cutting across a face, the

sumping feed effecting element lies at opposite sides of the central longitudinal vertical plane of the machine.

So far as concerns the truck driving mechanism likewise driven by the shaft 56, it will 75 be noted that in Fig. 1 I have shown the machine to be mounted upon a suitable truck frame 95, which is in turn carried upon truck wheels 96 adapted to have their axles 97 driven through a chain and sprocket connection 98 connection between the axles and through a second chain and sprocket connection 99 operatively connected between a sprocket 100 on either side of the rear axle and the truck driving sprocket 62. By this 80 arrangement, it will be noted that as the machine is moved forward on the truck during the process of unloading i. e. when the front end of the chain 82 is fixed to the face and the shaft 56 set in operation, the chain of the 85 connection 99 is automatically loosened so that it may be readily removed as the sprocket 62 passes over the sprocket 100, and that, conversely, when the machine is moved rearward as when it is being loaded onto the truck, i.e. when the rear end of the chain 82 is connected to the chain fork 101 on the truck and the shaft 56 is set in operation, the 90 chain 99 may be readily applied to the sprocket 62 as the latter moves over the sprocket 100, and later automatically tensioned by the further rearward movement of the machine on the truck. In this connection, it will be noted, moreover, that the movement of the machine is preferably limited by a 95 stop 102 formed on the truck and engageable with a cooperating stop 103 on the machine. Referring more particularly to the truck driving sprocket 62, it will be noted that I have 100 herein illustrated a clutch for connecting the same to or disconnecting the same from the shaft 56; in Figs. 3 and 7 showing the same and the sleeve 61 to be provided with cooperating clutch teeth 104. Attention is also directed to the fact that I have herein also provided the aperture 105 through which the bolt 105 91 extends, with a lateral enlargement 106 so that, when desired, by simply adjusting the bolt 91, as for instance by the use of an ordinary cutter bit wrench, the sprocket 62 may be shifted relative to the shaft 56 in such a manner as to connect or disconnect its clutch teeth and thereby connect or disconnect the truck driving mechanism and thus enable the 110 feeding mechanism or the truck driving 115 mechanism to be used independently.

In my improved construction, it will also be noted that all parts of the electrical equipment, including the motor and its controller, are readily accessible. In connection with 120 the motor, it will be observed that the field of the same is built up with plates 107 forming an internal herein rectangular box-like structure or frame open at its ends and riveted or otherwise suitably attached to the 125

side plates 17 and to the bed plate 3, as illustrated in Figs. 3 and 4, in such a manner as to increase the rigidity of the frame. It will also be noted that pole pieces 108 are fixed to these members 107 in a well known manner 5 and that these pole pieces and pole faces 109 are attached to the frame by the same means, as for instance by bolts 110, having their nuts accessible from the exterior of the side member 17, the field coils 111 being carried in a 10 usual manner between the members 107 and the pole faces 109. Attention is also directed to the fact that as shown in Fig. 3 the armature shaft 112 is journaled at its rear end in a suitable bearing 113 formed in a trans- 15 verse frame member 114, dividing the casing into motor and feeding mechanism compartments. As shown, the rear end of the shaft 112 is conical and splined at 115 in the correspondingly recessed hub 116 of the bevel pinion 12, which is in turn attached thereto by a thrust bolt 117, while this hub 116 is in turn journaled in a suitable bearing 118 of bracket form attached by bolts 119 to the member 114. 20 As shown, in Fig. 4 the opposite end of the armature shaft is splined at 120 to a radial and thrust bearing 121 carried on a suitable bearing flange 122 formed on a removable end plate 123, the position of the shaft being controlled by a thrust bolt 124 which is in turn 25 enclosed by a suitable plate 125 connected to the plate 123 in any suitable manner, as for instance by bolts 126. As shown, these two plates 123 and 125 are also seated in a suitable enlarged opening 127 in the front head or end 128 of the motor casing which is preferably provided with one or more slots 129 adapted to register in one position with lugs 130 on the plate 123, so that these plates may be rotated to a releasing position and removed 30 when desired. By this improved construction it will be noted that it is possible to bore out the several longitudinal apertures in the plate 128, the pole pieces 108, and the 35 plate 114, in a simple manner involving only one setting up of the boring machine, and that it is also possible to remove the armature by simply releasing the plates 123, 125, releasing the connection 117, and then with- 40 drawing the armature toward the front of the bar without removing the front head, a feature of decided advantage in that it permits the armature to be removed at the face even in low coal and thereby eliminates the 45 loss of time and production as well as the expense heretofore necessary and resulting from sending the whole machine to the shop. So far as the controlling mechanism is concerned, it will be noted that the same may 50 be housed in a suitable controller box 131 fixed to the rear end plate 131' of the machine casing at a point between the two sets of 55 sheaves 88, 89, and in which position the reversing switch handle 132 and the rheostat handle 133 are very conveniently located for 60 the operator, whose normal station is at the rear of the machine. 65

In the operation of my improved construction, it will be noted that when it is desired to unload the machine from the truck, it is only necessary for the operator to throw out the clutch 104, and connect one end of the chain 82 around the chain driving sprocket 64, and the opposite end of the same to the face, whereupon, when the motor is started and connected to the fast feed, the machine will then be fed forward upon the truck. As the truck driving sprocket 62 passes over the sprocket 100, it will be observed that slack is inserted in the chain connection 99 so that the latter may be removed from the sprocket 62 and the machine unloaded in a well known manner and brought up to its desired summing position. For instance, if it is desired to sum at the right hand rib 70 and cut from right to left of the room, as shown in Fig. 12, the machine is brought to the dotted position shown in Fig. 12. Then, after the cutter chain is started and the slow feed thrown in, the machine is summed into the coal until its bar is entirely under the face. An alternative arrangement for summing is shown in Fig. 13, in which it will be noted that instead of utilizing the advance flexible portion of the flexible feeding means to draw 75 the machine into the face, the receding portion may be used. When summing as in Fig. 12 the chain will be reeved relative to the sprocket 64 as indicated in dotted lines in Fig. 2. When summing according to the method of Fig. 13 the chain will be disposed as indicated in full lines in Fig. 2. In cutting across the face from right to left the chain must be arranged as indicated in dotted lines in Fig. 2, so that if the summing method 80 of Fig. 13 is employed a rereeing after summing is essential, in order that the chain may be properly disposed for transverse cutting. During transverse cutting, the machine will of course be under the control of the controlling mechanism 55, 77, etc., above described, so that the operator may vary the movement or the angle of the machine as desired, to enable it to cut around obstructions. Obviously, after the transverse cut has been thus completed, the machine may also be returned to the truck, as usual, on its fast feed. It will also be evident that it will only be necessary to change the arrangement of the chain relative 85 to its driving sprocket 64 to reverse the direction of movement of either the fast or slow feeds of the machine at any time should this be necessary during the use of the slow feed, as during the cutting operation, or while the machine is being operated on its fast feed, 90 as when the same is being returned to the truck. Obviously, by a simple transposition of the feed sprockets and the truck driving sprocket, the machine may be adapted to sum at the left rib and cut from left to right, 95 100 105 110 115 120 125 130

as shown in Fig. 11, in which case the machine is adapted to be controlled in the same manner as above described.

Considering more specifically the operation of the feed mechanism, it will be observed that through suitable manipulation of the control members 55 and 77, it is possible to cause the rotation of the feed operating member 64 at four speeds, each different from 10 the other and two in each direction. More particularly it will be observed that by moving the controlling member 55 to the right (Fig. 3) to connect the gear 46 to the sleeve 50, and moving the controlling member 77 15 to the right to connect the gear 74 to the shaft 56, the feed sprocket 64 carried on the shaft will be rotated at a relatively slow speed, called the sumping speed, suitable for sumping or transverse cutting under favorable 20 conditions. By then throwing the control lever 55 to the right to disconnect the gear 46 and connect the gear 48, an even slower speed, called the cutting speed, may be obtained which is adapted for transverse cutting or, if desired, for sumping under difficult 25 conditions. Both of these feeds, it will be noted, are in the same direction, and it will be also noted that during either of these feeds, the operator is enabled to reverse the 30 direction of feeding at any desired time by simply reversing the reeving of the feed chain relative to the sprocket 64, the machine being fed in one direction when the feed chain engages the member 64 and the guide 35 sprocket 86 and in the reverse direction when it engages the member 64 and the guide sprocket 87. Here attention is also directed to the fact that each of these two feeds and its reverse feed obtained by this rearrangement 40 of the feed chain is likewise obtainable whether the machine is operating as a right or left hand machine, the transposition of the feed operating member and its cooperating guides or guide permitting the machine 45 to be fed to the right or left whenever desired without in any way interfering with the several feeds mentioned. By further manipulating the control members 55 and 77, and, more particularly, by throwing the 50 member 55 to the left to connect the gear 48 to the sleeve 50 and throwing the member 77 to the left to connect the sleeve 50 to the shaft 56, a still further speed, called the moving speed, may be obtained, the feed operating 55 member 64 then being rotated in a reverse direction at a speed, higher than either the sumping speed or cutting speed, which is especially adapted to use in moving the machine before and after cutting, and when at 60 the face, the higher speed enabling the machine to be moved appreciably faster and consequently reducing the time required in the moving operations of the machine before and after cutting. With the control members 65 55 and 77 in the position indicated for this

moving speed, it will also be evident that by simply throwing the control member 55 to the right to disconnect the gear 48 and connect the gear 46 to the sleeve 50, the shaft 56 will still be rotated in a reverse direction and at an even faster speed, called the fast speed, 70 adapted to move the machine very rapidly and more particularly adapted to use in the truck driving operation. In connection with the moving feed and the fast feed just described, it will also be observed that these two feeds are in the same direction, and that this direction is opposite to that of the sumping feed and cutting feed. In this instance, 75 also, it will be observed that each of these feeds may also be reversed by reversely reeving the feed chain and that each feed is obtainable whether the machine is moving to the right or left. Attention is also directed to the fact that through the provision of my improved frictional controlling mechanism, 80 it is possible for the operator further to vary any of the four speeds mentioned as desired by releasing or tightening the friction as 85 may be necessary.

Considering the operation of the truck driving mechanism more specifically, it will be evident that by connecting the truck driving sprocket 62 to the shaft 56, that sprocket may be rotated from and through the feeding mechanism at any one of the several speeds mentioned above. Thus it will be observed that the truck driving sprocket may be driven in such a manner as to move the truck at either of two forward speeds or at 90 either of two reverse speeds, either set of which may be reversed by reversing the motor in such a manner as to give the desired wide range of speeds to adapt the truck movement to the varying conditions of track and the like found in the ordinary mine, the fast speeds being valuable for use under good track conditions and permitting the movement of the apparatus from one place to another to be expedited, while the truck speeds 95 corresponding to the sumping and feed speed are adapted for use on less satisfactory track conditions or under conditions where it is desirable to propel the truck slowly, as for instance crossing poor track, pushing mine cars before the truck, etc. Here, attention is again directed to the fact that each of the four truck speeds is capable of being further modified by the operator through movement 100 of the friction controlling member 55 to cause the friction to release or grip to a greater or less extent as may be necessary, the construction being such that the operator is thus able to graduate the speed to any desired 105 degree. In this connection, attention is also directed to the fact that the operator through a reverse movement of this member 55 at any time may brake the truck and thereby further regulate the speed thereof independently of 110 115 120 125 130

the truck driving mechanism, if necessary bringing the truck to an abrupt stop.

By the use of my improved construction, it will be observed that during cutting, one bend in the tight side of the chain is eliminated, thereby materially reducing wear on the chain links and friction on the corner guide members. It will also be noted that as the machine is adapted to move in either direction either during cutting to the right or the left, by a simple change in the wrapping of the chain relative to the feed driving sprocket, all necessity for special reverse feeding mechanism is eliminated, at the same time that the flexibility of operation is increased. By my improved construction, it will also be noted that the number of rotating shafts is reduced to a minimum, and that all of the parts of the machine are exceedingly accessible, so that they may be assembled with the greatest facility or removed with like facility whenever desired. So far as the cost of the mechanism is concerned, it will also be observed that the same is of such an improved and simplified type that the entire cost of the machine may be materially reduced at the same time that the serviceability of the machine is retained or improved. These and other advantages of my improved construction will, however, be clearly apparent to those skilled in the art.

While I have in this application specifically described one embodiment which my invention may assume in practice, it will be understood that this form of the same is used for illustrative purposes only, and that the invention may be modified and assume various other forms without departing from its spirit or the scope of the appended claims.

What I claim as new and desire to secure by Letters Patent is:

1. In a mining machine, a cutter, a frame supporting the same and slidable over a mine bottom during cutting, and feeding mechanism for effecting feeding and guiding of said cutter and frame and operative to effect bodily movement of said cutter during cutting in a path parallel to a working face while substantially perpendicular thereto, including flexible feeding means adapted to be extended to a fixed point extraneous to the frame, and a feed operating member on said frame cooperating directly with said flexible feeding means to effect bodily translatory movement of said cutter relative to said fixed point and disposable selectively in a plurality of different operative positions on the frame in each of which the same is rotatable on an axis stationary with respect to said frame.

2. In a mining machine, a cutter, a frame supporting the same and slidable over a mine bottom during cutting, and feeding mechanism for effecting movement of said cutter and frame operative to sump said cutter into a working face and effect movement thereof

in a direction parallel to said face while substantially perpendicular thereto during cutting, including flexible feeding means adapted to be extended to a fixed point extraneous to the frame, and a feed operating member on said frame cooperating directly with said flexible feeding means to effect translatory movement of said cutter relative to said fixed point and disposable selectively in a plurality of different operative positions on the frame in each of which the same is rotatable on an axis stationary with respect to said frame.

3. In a mining machine, a cutter, a frame supporting the same and slidable over a mine bottom during cutting, and feeding mechanism for effecting movement of said cutter and frame operative to sump said cutter longitudinally into a working face and to effect movement thereof in a direction parallel to said face while substantially perpendicular thereto during cutting, including flexible feeding means adapted to be extended to a fixed point extraneous to the frame, and a feed operating member on said frame cooperating directly with said flexible feeding means to effect movement of said cutter relative to said fixed point and disposable selectively in a plurality of different operative positions on the frame in each of which the same is rotatable on an axis stationary with respect to said frame, whereby in different directions of cutting said feed operating member and said flexible feeding means may occupy similar positions with respect to said machine and its path of movement.

4. In a mining machine, a cutter, a frame supporting the same and slidable over a mine bottom during cutting, and feeding mechanism for effecting feeding and guiding of said cutter and frame and operative to effect bodily movement of said cutter during cutting in a path parallel to a working face while substantially perpendicular thereto, including flexible feeding means adapted to be extended to a fixed point extraneous to the frame, and a feed operating member on said frame cooperating directly with said flexible feeding means to effect translatory movement of said cutter relative to said fixed point and disposable selectively in a plurality of different operative positions on the frame in each of which the same is rotatable on a horizontal axis stationary with respect to said frame.

5. In a mining machine, a cutter, a frame supporting the same and slidable over a mine bottom during cutting, and feeding mechanism for effecting feeding and guiding of said cutter and frame and operative to effect movement of said cutter during cutting in a path parallel to a working face while substantially perpendicular thereto, including flexible feeding means adapted to be extended to a fixed point extraneous to the frame, and a feed operating member on said frame cooper-

ating directly with said flexible feeding means to effect translatory movement of said cutter relative to said fixed point and disposable selectively in a plurality of different operative 5 positions on the frame in each of which the same is rotatable on a transverse axis stationary with respect to said frame

6. In a mining machine, a cutter, a frame supporting the same and slidable over a mine bottom during cutting, and feeding mechanism for effecting feeding and guiding of 10 said cutter and frame and operative to effect movement of said cutter during cutting in a path parallel to a working face while substantially perpendicular thereto, including 15 flexible feeding means adapted to be extended to a fixed point extraneous of the frame, and a feed operating member on said frame cooperating directly with said flexible feeding 20 means to effect translatory movement of said cutter relative to said fixed point and disposable selectively in a plurality of operative positions on opposite sides of the frame in each 25 of which the same is rotatable on an axis stationary with respect to the frame.

7. In a mining machine, a cutter, a frame supporting the same and slidable over a mine bottom during cutting, and feeding mechanism for effecting feeding and guiding of 30 said cutter and frame and operative to effect movement of said cutter during cutting in a path parallel to a working face while substantially perpendicular thereto, including 35 flexible feeding means adapted to be extended to a fixed point extraneous to the frame, a feed operating member on said frame cooperating directly with said flexible feeding means to effect translatory movement of said cutter relative to said fixed 40 point, and guiding means cooperating with said feed operating member to maintain said flexible means in operative relation thereto, said feed operating member and said guiding means being disposable selectively in a 45 plurality of different positions on the frame, in each of which said feed operating member is rotatable on an axis stationary with respect to the frame.

8. In a mining machine, a cutter, a frame 50 supporting the same and slidable over a mine bottom during cutting, and feeding mechanism for effecting feeding and guiding of said cutter and frame and operative to effect movement of said cutter during cutting 55 in a path parallel to a working face while substantially perpendicular thereto, including flexible feeding means adapted to be extended to a fixed point extraneous to the frame, a feed operating member on said 60 frame cooperating directly with said flexible feeding means to effect movement of said cutter relative to said fixed point, and guiding means cooperating with said feed operating member to maintain said flexible means 65 in operative relation thereto, said feed oper-

ating member and said guiding means being disposable selectively in a plurality of different positions on the frame, in each of which said feed operating member is rotatable on a horizontal axis stationary with respect to the frame.

9. In a mining machine, a cutter, a frame supporting the same and slidable over a mine bottom during cutting, and feeding mechanism for effecting feeding and guiding of said cutter and frame and operative to effect movement of said cutter during cutting in a path parallel to a working face while substantially perpendicular thereto, including 70 flexible feeding means adapted to be extended to a fixed point extraneous to the frame, a feed operating member on said frame cooperating directly with said flexible feeding means to effect movement of said cutter relative to said fixed point, and guiding means cooperating with said feed operating member to maintain said flexible means in operative relation thereto, said feed operating member and said guiding means being disposable selectively in a plurality of different positions on the frame, in each of which said feed operating member is rotatable on a transverse axis stationary with respect to the frame.

10. In a mining machine, a cutter, a frame supporting the same and slidable over a mine bottom during cutting, and feeding mechanism for effecting feeding and guiding of said cutter and frame and operative to effect movement of said cutter during cutting in a path parallel to a working face while substantially perpendicular thereto, including 80 flexible feeding means adapted to be extended to a fixed point extraneous to the frame, a feed operating member on said frame cooperating directly with said flexible feeding means to effect movement of said cutter relative to said fixed point, and guiding means cooperating with said feed operating member to maintain said flexible means in operative relation thereto, said feed operating member and said guiding means being disposable selectively in a plurality of different positions on the frame, in each of which said feed operating member is rotatable on a transverse axis stationary with respect to the frame.

11. In a mining machine, a cutter, a frame supporting the same and slidable over a mine bottom during cutting, and feeding mechanism for effecting feeding and guiding of said cutter and frame and operative to effect movement of said cutter during cutting in a path parallel to a working face while substantially perpendicular thereto, including 90 flexible feeding means adapted to be extended to a fixed point extraneous to the frame, a feed operating member on said frame cooperating directly with said flexible feeding means to effect movement of said cutter relative to said fixed point, and guiding means cooperating with said feed operating member to maintain said flexible means in operative relation thereto, said feed operating member and said guiding means being disposable selectively in a plurality of different positions on the frame, in each of which said feed operating member is rotatable on a transverse axis stationary with respect to the frame.

12. In a mining machine, a cutter, a frame with which said cutter moves during cutting, and truck driving mechanism on said frame including a truck driving member adapted for connection with the running gear of a truck and disposable in a plurality of positions on said frame in each of which it is rotatable by power.

13. In a mining machine, a cutter frame, a feed operating member thereon, a truck driving member thereon adapted for operative connection with the running gear of a truck, each of said members being movable 125

- with said cutting frame during cutting, and means whereby each of said members may be operatively disposed and actuated in a plurality of positions on said frame.
13. In a mining machine, a cutter frame, feed and truck drive transmission mechanism on said frame, a feed operating member driven by said mechanism, and a truck driving member driven by said mechanism and adapted for operative connection with the running gear of a truck and interchangeable with said feed operating member.
14. In a mining machine, a frame, cutting mechanism thereon, feeding mechanism thereon including a feed operating member, and truck driving mechanism thereon bodily movable during cutting with the cutting and feeding mechanism and including a truck driving member disposable in different positions and adapted for operative connection with the running gear of a truck, each of said feed operating and truck driving members extending laterally from said frame.
15. In a mining machine, a frame, cutting mechanism thereon, feeding mechanism thereon including a feed operating member, truck driving mechanism thereon bodily movable during cutting with said cutting and feeding mechanism including a truck driving member adapted for operative connection with the running gear of a truck, and means whereby said members may be interchanged at will.
16. In a mining machine, a frame, cutting mechanism thereon, feeding and truck driving mechanism thereon including feed operating and truck driving members bodily movable during cutting with said cutting and feeding mechanisms and extending laterally from opposite sides of said frame, said truck driving member being adapted for operative connection with the running gear of a truck, and means whereby said members may be interchanged at will.
17. In a mining machine, a cutter frame, cutting mechanism thereon, feeding mechanism thereon including a feed operating member, truck driving mechanism thereon including a truck driving member interchangeable with said feed operating member, said truck driving member being adapted for operative connection with the running gear of a truck, each of said members extending laterally from said frame, and means for controlling one of said members.
18. In a mining machine, a frame, cutting mechanism thereon, feeding mechanism thereon including a feed operating member, truck driving mechanism thereon including a truck driving member interchangeable with said feed operating member, said truck driving member being adapted for operative connection with the running gear of a truck, each of said members extending laterally from said frame, and means for rendering said members operative and inoperative.
19. In a mining machine, a frame, cutting mechanism thereon, feeding mechanism thereon including a feed operating member, truck driving mechanism thereon including a truck driving member, said truck driving member being adapted for operative connection with the running gear of a truck and each of said members extending laterally from said frame, a motor for driving said members, and means for varying the speed of each of said members, permitting drive thereof at different speeds, while said motor speed remains constant.
20. In a mining machine, a cutter frame including a rigidly connected longitudinally extending cutter bar, feeding mechanism thereon including a single flexible feeding member normally having free extremities and a rotatable feed operating member, and means including guiding means adjacent said feed operating member whereby said flexible member may, in any position thereof with respect to said operating member, be reversely operatively connected to said operating member to change the direction of feed while said feed operating member rotates in one direction and maintained in operative relation thereto.
21. In a mining machine, a cutter frame including a rigidly connected longitudinally extending cutter bar, feeding mechanism thereon including a single flexible feeding member normally having free extremities and a single rotatable feed operating member, and means including guiding means adjacent said feed operating member whereby said flexible member may be reversely operatively connected and maintained in operative relation to said operating member to feed said frame in different directions and in one relation reversibly connectible to said operating member to change the direction of feed while said feed operating member rotates in one direction.
22. In a mining machine, a cutter frame including a rigidly connected longitudinally extending cutter bar, feeding mechanism thereon including a single flexible feeding member normally having free extremities and a rotatable feed operating member, and means including guiding means adjacent said feed operating member whereby said flexible member may be reversely operatively connected and maintained in operative relation to said operating member to feed said frame in different directions and in either relation reversibly connectible to said operating member to change the direction of feed while said feed operating member rotates in one direction.
23. In a mining machine, a cutter frame, feeding mechanism thereon including a single flexible feeding member and a feed operating

member rotatable on a horizontal axis and cooperating directly with said feeding member, and means whereby said flexible member may be reversely operatively connected to said operating member to change the direction of feed.

24. In a mining machine, a cutter frame, feeding mechanism thereon including a single flexible feeding member and a feed operating member therefor rotatable on a horizontal axis, and cooperating directly with said feeding member and means including alternatively engageable guiding members whereby said flexible member may be reversely operatively connected to said operating member to change the direction of feed.

25. In a mining machine, a cutter frame including a rigidly connected longitudinally extending cutter bar, feeding mechanism thereon selectively operable to feed said frame transversely to the right or left and to determine the angle of the bar to a face during cutting and including a single flexible feeding member having advance and receding portions and a rotatable feed operating member cooperating directly with said flexible member and means whereby said member may be reversely connected to vary the direction of feed to effect the drawing in of either portion thereof at the same speed during either the right or left hand feeding.

26. In a mining machine, a cutter frame, feeding mechanism thereon including a feed operating member rotatable on a horizontal axis and a single flexible feeding member reversely connectible therewith to feed said frame in either direction and to determine the angle thereof during such feed, and guiding means for said flexible member disposed at one end of said frame.

27. In a mining machine, a cutter frame, feeding mechanism thereon including a feed operating member rotatable on a horizontal axis and a single flexible feeding member reversely connectible therewith to feed said frame in either direction and to determine the angle thereof during such feed, and a plurality of alternatively operative guiding means on the rear end of said frame.

28. In a mining machine, a frame, cutting mechanism thereon, feeding mechanism thereon including a flexible feeding member normally extending laterally in opposite directions from opposite ends of said frame and a laterally extending feed operating member, and guiding means for said flexible member for directing said frame transversely during cutting including a laterally extending guiding member disposed above said operating member.

29. In a mining machine, a frame, cutting mechanism fixed thereon, feeding mechanism for said frame including a flexible feeding member normally extending laterally in opposite directions from opposite ends of said

frame and a laterally extending feed operating member, and guiding means for said flexible member for directing said frame transversely during cutting including a laterally extending guiding member disposed 70 wholly below said operating member.

30. In a mining machine, a frame, cutting mechanism fixed thereon, feeding mechanism for said frame including a flexible feeding member and a laterally extending feed operating member, and guiding means for said flexible member for directing said frame transversely during cutting including cooperating laterally extending guiding members disposed above and below said operating member.

31. In a mining machine, a frame, cutting mechanism thereon, feeding mechanism thereon including a flexible feeding member and a laterally extending feed operating member, guiding means for said flexible member for directing said frame transversely during cutting including a laterally extending guiding member disposed adjacent 85 said member, and means whereby said operating and guiding means may be operatively disposed in a plurality of positions on said frame.

32. In a mining machine, a frame slidable on the bottom, cutting mechanism fixed thereon, feeding mechanism thereon including a flexible feeding member and a laterally extending feed operating member, guiding means for said flexible member including a laterally extending guiding member disposed 95 adjacent said member, and means whereby said operating and guiding means may be operatively disposed on either side of said frame.

33. In a mining machine, a frame slidable 105 on the bottom, cutting mechanism fixed thereon, feeding mechanism thereon including a flexible feeding member and a laterally extending feed operating member, guiding means for said flexible member including a laterally extending guiding member disposed above said member, and means whereby said members may be operatively disposed on either side of said frame.

34. In a mining machine, a frame, cutting mechanism thereon, feeding mechanism thereon including a flexible feeding member and a laterally extending feed operating member, guiding means for said flexible member for directing said frame transversely during cutting including a laterally extending guiding member disposed below said member, and means whereby said member may be operatively disposed on either side of said frame.

35. In a mining machine, a cutter frame, cutting mechanism thereon, feeding mechanism thereon including a flexible feeding member and a laterally extending feed operating member, guiding means for said flexible

- member for directing said frame transversely during cutting including cooperating laterally extending guiding members disposed above and below said member, and means whereby 5 said members may be operatively disposed on either side of said frame.
36. In a mining machine, a frame slidable on its bottom on a mine bottom, cutting mechanism thereon including a rigidly connected longitudinally extending cutter bar, and feeding mechanism thereon for feeding said frame bodily laterally in either direction, including in either arrangement thereof a flexible feeding member, a feed operating member 10 extending laterally from one side of said frame and cooperating directly with said flexible feeding member, and guiding means for said flexible feeding member adjacent said feed operating member and also at the 15 opposite ends of said frame.
37. In a mining machine, a frame, cutting mechanism thereon, feeding mechanism thereon including flexible feeding means and a laterally disposed feed operating member 20 adapted to cooperate directly with said flexible feeding means, cooperating guiding means for said flexible feeding means disposed above said feed operating member, and cooperating guiding means for said flexible 25 feeding means disposed at the opposite ends of one side of said frame.
38. In a mining machine, a frame, cutting mechanism thereon, feeding mechanism thereon including flexible feeding means and 30 a laterally disposed feed operating member adapted to cooperate directly with said flexible feeding means, cooperating guiding means for said flexible feeding means disposed below said feed operating member, and 35 cooperating guiding means for said flexible feeding means disposed at the opposite ends of one side of said frame.
39. In a mining machine, a frame, cutting mechanism thereon, feeding mechanism thereon including flexible feeding means and 40 a laterally disposed feed operating member adapted to cooperate directly with said flexible feeding means, and cooperating guiding means for said flexible feeding means alternatively engageable thereby and disposed 45 adjacent said feed operating member and on the same side of a vertical plane through the axis of said feed operating member.
40. In a mining machine, a frame, cutting mechanism thereon, feeding mechanism thereon including a flexible feeding member 50 and a laterally disposed feed operating member adapted to cooperate directly with said flexible feeding means, cooperating guiding means for said flexible member disposed above and below said feed operating member, and 55 cooperating guiding means for said flexible member disposed at the opposite ends of said frame.
41. In a mining machine, a frame, cutting mechanism thereon, feeding mechanism thereon including a flexible feeding member and a laterally disposed feed operating member adapted to cooperate directly with said flexible feeding means, cooperating guiding 60 means for said flexible member disposed above and below said feed operating member, and cooperating guiding means for said flexible member disposed at the opposite ends of said frame.
42. In a mining machine, a frame, cutting mechanism thereon, feeding mechanism thereon including laterally disposed adjacent feed operating and guiding members adapted for direct cooperation with flexible feeding means, means whereby said members may be 65 disposed at either side of said frame, and cooperating guiding means including angularly disposed guiding members located at the opposite sides of the rear end of said frame.
43. In a mining machine, a frame, cutting mechanism thereon, feeding mechanism thereon including a single flexible feeding member and a directly cooperating rotatable laterally extending feed operating member, and guiding means for said flexible feeding member including guiding members disposed at opposite ends of said frame and a laterally extending guiding member disposed above 70 said feed operating member.
44. In a mining machine, a frame slidable on the bottom, cutting mechanism thereon, feeding mechanism thereon including a single flexible feeding member and a directly cooperating rotatable laterally extending feed operating member, and guiding means for 75 said flexible feeding member including guiding members disposed at opposite ends of said frame and a laterally extending guiding member disposed wholly below said feed operating member.
45. In a mining machine, a frame, cutting mechanism thereon, feeding mechanism thereon including a single flexible feeding member and a rotatable laterally extending feed operating member cooperating directly with said flexible feeding member, and guiding means for said flexible feeding member including guiding members disposed at opposite ends of said frame and laterally extending guiding members disposed above and below said feed operating member.
46. In a mining machine, a frame, cutting mechanism thereon, feeding mechanism thereon including a single flexible feeding member and a rotatable laterally extending feed operating member cooperating directly with said flexible feeding member, and guiding means for said flexible feeding member including guiding members disposed at opposite ends of said frame and laterally extending guiding members disposed above and below said feed operating member, said guiding members at the rear end of said frame being relatively angularly disposed.

47. In a mining machine, a frame, cutting mechanism thereon, feeding and guiding mechanism thereon for feeding said frame transversely during cutting including a feed 5 operating member rotatable on a transverse axis, and truck driving mechanism operatively connected to said feeding mechanism and including a transposable truck driving member interchangeable in position with 10 said feed operating member and likewise rotatable on a transverse axis and adapted for operative connection with the running gear of a truck.

48. In a mining machine, a frame, cutting 15 mechanism fixed thereon, feeding mechanism thereon including a flexible feeding member and a feed operating member cooperating therewith and rotatable on a transverse axis, and truck driving mechanism operatively 20 connected to said feeding mechanism and bodily movable with said frame including a transposable truck driving member likewise rotatable on a transverse axis and adapted for operative connection with the 25 running gear of a truck, said members being located on opposite sides of said frame.

49. In a mining machine, a frame, cutting mechanism fixed thereon, feeding mechanism thereon including a transverse driving shaft 30 and a feed operating member rotatable on a transverse axis, a flexible feeding member with which said feed operating member cooperates, and truck driving mechanism operatively connected to said feeding mechanism 35 and bodily movable with said frame including a truck driving member likewise rotatable on a transverse axis and operatively connectible at will to said driving shaft, said truck driving member being adapted for operative 40 connection with the running gear of a truck.

50. In a mining machine, a frame, cutting mechanism fixed thereon, feeding mechanism thereon including a transverse driving shaft and a feed operating member disposed on one 45 end of said shaft, and truck driving mechanism operatively connected to said feeding mechanism and bodily movable with said frame including a truck driving member likewise rotatable on a transverse axis and disposed on the opposite end of said shaft, said truck driving member being adapted for operative 50 connection with the running gear of a truck.

51. In a mining machine, a frame, cutting 55 mechanism fixed thereon, feeding mechanism thereon including a feed operating member rotatable on a transverse axis, truck driving mechanism operatively connected to said feeding mechanism and bodily movable with 60 said frame including a transposable truck driving member interchangeable in position with said feed operating member and likewise rotatable on a transverse axis and operatively connectible with the running gear 65

of a truck, and means for controlling said members.

52. In a mining machine, a frame, cutting mechanism thereon, feeding mechanism including a feed operating member 70 rotatable on a transverse axis, truck driving mechanism operatively connected to said feeding mechanism and including a transposable truck driving member interchangeable in position with said feed operating member and likewise rotatable on a transverse axis 75 and adapted to constitute a driving member for the running gear of a truck, and means whereby one of said members may be operated while the other remains stationary. 80

53. In a mining machine, a frame, cutting mechanism fixed thereon, feeding mechanism thereon including a transversely disposed shaft, a laterally extending feed operating member connected to said shaft, and truck 85 driving mechanism movable with said frame operatively connected to said shaft and including an oppositely disposed laterally extending transposable truck driving member interchangeable in position with said feed 90 operating member and adapted for connection in driving relation to the running gear of a truck.

54. In a mining machine, a frame, cutting mechanism fixed thereon, feeding mechanism 95 thereon including a transversely disposed shaft, a laterally extending feed operating member connected to said shaft, truck driving mechanism movable with said frame and including a laterally disposed truck driving 100 member operatively connected to the opposite end of said shaft and adapted for operative connection in driving relation to the running gear of a truck, and means whereby said members may be interchanged. 105

55. In a mining machine, a frame, cutting mechanism thereon, feeding mechanism thereon including a transversely disposed shaft, a rotatable feed operating member on one end of said shaft, a rotatable truck driving member on the opposite end of said shaft adapted for operative connection in driving relation to the running gear of a truck, and means whereby said members may be operated together or one by itself. 115

56. In a mining machine, a cutter frame, cutting mechanism thereon, feeding mechanism thereon including a transversely disposed shaft, a rotatable feed operating member on one end of said shaft, a rotatable truck driving member on the opposite end of said shaft adapted for operative connection in driving relation to the running gear of a truck, and means for independently controlling one of said members. 120

57. In a mining machine, a frame, cutting mechanism movable therewith during cutting, feeding mechanism on said frame adapted to effect feeding during cutting and including a transversely disposed shaft, a 125 130

- transversely disposed feed operating member operatively connected to said shaft, an oppositely disposed truck driving member operatively connectible to said shaft and mounted on said frame and adapted for operative connection with the running gear of a truck, and mechanism operative to control the speed and direction of rotation of said shaft.
- 5 58. In a mining machine, a frame, cutting mechanism movable therewith during cutting, feeding mechanism on said frame including a transversely disposed shaft, a transversely disposed feed operating member operatively connected to said shaft, an oppositely disposed truck driving member operatively connectible to said shaft and mounted on said frame and adapted for operative connection with the running gear of a truck,
- 10 59. In a mining machine, a frame, cutting mechanism movable therewith during cutting, feeding mechanism on said frame including a transversely disposed shaft, a transversely disposed feed operating member operatively connected to said shaft and adapted to cooperate with a flexible feeding member having a free end adapted for connection to a stationary point, an oppositely disposed truck driving member operatively connectible to said shaft and adapted for operative connection in driving relation to the running gear of a truck, and separate means for controlling one the speed and the other the direction of rotation of said feed operating member and of said truck driving member.
- 15 60. In a mining machine, a casing, cutting mechanism thereon, a feed operating member adapted to cooperate directly with flexible feeding means on said casing, a motor therein, and operative connections within said casing between said motor and said feed operating member including a variable speed reversing mechanism and a laterally disposed driving shaft coaxially located with certain of the elements of said mechanism and removable laterally through the side of said casing.
- 20 61. In a mining machine, a casing, cutting mechanism thereon, a feed operating member adapted to cooperate directly with flexible feeding means, a truck driving member, a motor, and operative connections within said casing between said motor and said feed operating and truck driving members including a laterally disposed member removable laterally through the side of said casing.
- 25 62. In a mining machine, a frame, cutting mechanism thereon, a transverse shaft journaled on said frame, combined feeding
- and truck drive transmission mechanism operatively connectible to said shaft, feed operating and truck driving members operatively connected to said shaft, said feed operating member being adapted to direct cooperation with a flexible feeding element, and said truck driving member being adapted for operative connection with the running gear of a truck, and both of said members movable bodily with said cutting mechanism during cutting, and controlling mechanism controlling the connection of one of said members to said shaft.
- 30 63. In a mining machine, a frame, cutting mechanism thereon, a transverse shaft journaled on said frame, combined feed and truck driving transmission mechanism operatively connected to said shaft, a motor, feed operating and truck driving members operatively connected to said shaft, said feed operating member being adapted for direct cooperation with a flexible feeding element and said truck driving member being adapted for operative connection with the running gear of a truck and said mechanism including a plurality of controlling members controlling the speed and direction of rotation of said shaft while said motor rotates at uniform speed in one direction.
- 35 64. In a mining machine, a frame, cutting mechanism thereon, a motor on said frame, a transverse driving shaft thereon, a truck driving member operatively connected to said shaft, a plurality of transversely disposed studs disposed between said shaft and motor, and fast and slow speed transmission mechanism carried on said studs and shaft and operatively connected between said motor and said shaft.
- 40 65. In combination, a mining machine including a transverse shaft having laterally extending separate feeding and truck driving members thereon, the latter member being adapted for operative connection in driving relation to the running gear of a truck, cooperating mechanism including reversing and change-speed gearing for controlling the speed and direction of rotation of said transverse driving shaft, and a clutch between said laterally disposed truck driving member and said shaft.
- 45 66. The combination with a mining machine slideable on a mine bottom during cutting and carrying a cutter bar and having feeding mechanism on said machine for feeding the same bodily laterally during cutting including a transverse shaft, of a laterally extending truck driving member, and driving connections between said truck driving member and said shaft including a friction clutch.
- 50 67. The combination with a mining machine slideable on a mine bottom during cutting and carrying a cutter bar and having feeding mechanism on said machine for feed-

ing the same bodily laterally during cutting including a transverse shaft, of a laterally extending truck driving member, and reversible driving connections between said truck driving member and said shaft including a friction clutch.

68. In a mining machine, a frame slidable on a mine bottom during a cutting operation, cutting mechanism thereon including a cutter bar rigidly connected thereto, feeding mechanism thereon, a longitudinally extending driving motor therefor including an armature and carried on said frame above the rear end of said bar and in front of said feeding mechanism, a motor casing on the front end of said frame having a front head, and means for permitting longitudinal withdrawal of said armature without removal of said head including an aperture in said head and an aperture closing member receivable therein and rotatable into interlocking engagement with said head.

69. In a mining machine, a machine frame having a surface on which it may slide over a mine bottom during cutting, cutting and feeding mechanism thereon including respectively a main gear rotatable on a vertical axis and a transverse gearing supporting member disposed above said gear, means for permitting lateral withdrawal of said transverse member through the side of said frame, and means for permitting subsequent vertical withdrawal of said gear.

70. In a mining machine, a machine frame supporting a motor casing and having a surface on which it may slide over a mine bottom during cutting, cutting and feeding mechanism thereon including respectively a main gear and a transverse gearing supporting member disposed above said gear, means for permitting lateral withdrawal of said transverse member through the side of said frame, means for permitting subsequent vertical withdrawal of said gear while said motor casing remains in position on said frame, and a cutter chain driving sprocket removable with said gear.

71. In a mining machine, a casing having a shoe upon which it is slidable over a supporting surface, a bed plate above said shoe, a motor comprising a field frame on said bed plate, and cutter chain driving mechanism in said casing comprising an upright member supported by said shoe, a rotatable main gear disposed coaxially with said member, a cutter chain driving sprocket disposed on said member in a plane beneath said bed plate and rotatable by said gear, and means whereby said sprocket may be removed from the top of said casing through said bed plate, said sprocket being removable without disturbing said field frame.

72. In a mining machine, a casing having a shoe, means forming an apertured bed plate above said shoe, a motor having a field frame

on said bed plate spaced longitudinally from the aperture therein, and cutter chain driving mechanism in said casing comprising an upright member supported by said shoe, a rotatable main gear disposed coaxially with said member, and a cutter chain driving sprocket disposed in a plane between said shoe and bed plate and rotatable by said gear and removable through the aperture in said bed plate.

73. In a mining machine, a casing having a shoe, means forming an apertured bed plate above said shoe, a motor having a field frame on said bed plate spaced longitudinally from the aperture therein, and cutter chain driving mechanism in said casing comprising an upright member supported by said shoe, a rotatable main gear disposed coaxially with said member, and a cutter chain driving sprocket disposed in a plane between said shoe and bed plate and rotatable by said gear and removable with said main gear through the aperture in said bed plate.

74. In a mining machine, a casing having a shoe, means forming an apertured bed plate above said shoe, a motor having a field frame on said bed plate spaced longitudinally from the aperture therein, and cutter chain driving mechanism in said casing comprising an upright member supported by said shoe, a rotatable main gear disposed coaxially with said member, a cutter chain driving sprocket disposed in a plane between said shoe and bed plate and rotatable by said gear and removable through the aperture in said bed plate, and means for closing said aperture.

75. A mining machine including a frame having a shoe slidable on a mine bottom, mining machine driving mechanism carried on said frame including a motor having a field structure, cutting mechanism driven by said driving mechanism and including a cutter chain driving sprocket disposed in a plane above said shoe, and means whereby said sprocket may be removed through the top of said frame without disturbing said field structure.

76. In a mining machine, the combination comprising a shoe, a stub supported thereon, an upper bed-plate, a main gear journaled on said stub, a bracket supported by said stub, a transverse member supported by said shoe and journaled in said bracket, and driving mechanism for said main gear carried on said transverse member.

77. In a mining machine, the combination comprising a shoe, a stub supported thereon, a main gear journaled on said stub, a bracket supported by said stub, a transverse stud supported by said shoe and journaled in said bracket, driving mechanism for said main gear carried on said transverse stud, and means whereby said stub may be withdrawn laterally through said driving mechanism.

78. In a mining machine, the combination

- comprising a frame, an upstanding stud supported thereon, a main gear journaled on said stud, feeding mechanism on said frame including a stud disposed transversely above 5 said main gear, driving connections for said main gear carried on said transverse stud, and means whereby said transverse stud may be withdrawn laterally through said frame.
79. In a mining machine, the combination 10 comprising a frame, a horizontally disposed main gear thereon, a plurality of transversely extending studs disposed over said gear, a transversely disposed shaft located in rear of said main gear, driving connections carried on one of said studs for said main gear and on both of said studs for said shaft, and means whereby said studs may be withdrawn laterally through said frame.
80. The combination with a mining 20 machine, of feeding mechanism therefor including a laterally extending feed operating member and a cooperating flexible feeding member, cooperating guiding means for said flexible feeding member for directing said machine transversely during cutting, and a plurality 25 of cooperating guiding means for said flexible member alternatively engageable by said member when the same is reversely reeved relative to said feed operating member.
81. The combination with a mining 30 machine slideable on a mine bottom during cutting and including a frame, of truck driving mechanism thereon including a motor and a truck driving member driven thereby, and means thereon between said motor and said member operable independently of motor control to rotate said member at a plurality of predetermined speeds in the same direction and rotating the same in the opposite direction at a different predetermined speed.
82. The combination with a mining machine slideable on a mine bottom during cutting and including a frame, of truck driving mechanism thereon including a motor and a truck driving 45 member driven thereby, and means thereon between said motor and said member operable independently of motor control to rotate said member at a plurality of predetermined speeds in one direction and rotating the same 50 at a plurality of different predetermined speeds in the opposite direction.
83. The combination with a mining machine slideable on a mine bottom during cutting and including a frame, of truck driving mechanism thereon including a motor and a truck driving member, means for rotating said member at a plurality of predetermined speeds in the same direction and rotating the same in the opposite direction at a different predetermined speed, and a friction clutch included in said means.
84. The combination with a mining machine slideable on a mine bottom during cutting and including a frame, of truck driving mechanism thereon including a motor and 65
- a truck driving member, means for rotating said member at a plurality of predetermined speeds in one direction and rotating the same at a plurality of different predetermined speeds in the opposite direction, and a friction clutch included in said means. 70
85. The combination with a mining machine, of feeding mechanism thereon operable to feed said machine and rotatable at a plurality of predetermined speeds in one direction and at a plurality of other predetermined speeds in an opposite direction, and truck driving mechanism thereon rotatable thereby at any of said predetermined speeds. 75
86. The combination with a mining machine, of feeding mechanism thereon operable to feed said machine and including a feed operating member adapted to cooperate directly with flexible means and rotatable at a plurality of predetermined speeds in one direction and at a plurality of other predetermined speeds in a reverse direction, and truck driving mechanism thereon rotatable thereby at one of said speeds. 80
87. The combination with a mining machine adapted to cut kerfs transversely of a working face from left to right or vice versa and having cutting mechanism including a cutter chain circulating in opposite directions during cutting in opposite directions, of feeding mechanism for propelling said cutting mechanism laterally along a face in either direction during cutting to cut oppositely extending kerfs including winding means rotatable on a plurality 90 of transverse axes and on opposite sides of said frame and flexible feeding means in either direction of feed having flexible advance and receding portions for respectively advancing and retarding the opposite ends of said frame, said flexible means when feeding said machine laterally in different directions having the advance flexible feeding portion wound in by differently located winding means. 95
88. The combination with a mining machine adapted to cut kerfs transversely of a working face from left to right or vice versa and including cutting mechanism including a cutter chain circulating in opposite directions during cutting in opposite directions, of feed operating means for directing said cutting mechanism into and transversely of a face in either direction during cutting including a plurality of feed operating power connections, feed operating means driven thereby and operative on transverse axes on opposite sides of said frame, and a single flexible feeding member operatively disposable in different relations during cutting in opposite directions and in each relation having flexible free extremities and a portion cooperating with said feed operating means. 100
89. The combination with a mining machine adapted to cut kerfs transversely 110
- 120
- 125
- 130

of a working face from left to right or vice versa and including cutting mechanism including a cutter chain circulating in opposite directions during cutting in opposite directions, of means for feeding said cutting mechanism to effect lateral cutting in either direction along a face including flexible feeding portions having free extremities and adapted to act alternatively during lateral cutting in opposite directions to advance and retard the opposite ends of said machine, and cooperating winding means rotatable by power at different points on said machine and at the same predetermined peripheral speed and operable when feeding said machine laterally in opposite directions to draw in different portions as the advance portion while permitting lengthening of different portions as the receding portion.

90. The combination with a mining machine adapted to cut kerfs transversely of a working face from left to right and vice versa and including cutting mechanism including a cutter chain circulating in opposite directions during cutting in opposite directions, of means for feeding said cutting mechanism to effect lateral cutting in either direction along a face including flexible feeding portions having free extremities and adapted to act alternatively during lateral cutting in opposite directions to advance and retard the opposite ends of said machine, and cooperating winding means rotatable by power on transverse axes at different points on said machine and at the same predetermined peripheral speed and operable when feeding said machine laterally in opposite directions to draw in different portions as the advance portion while permitting lengthening of different portions as the receding portion.

91. The combination with a mining machine adapted to cut kerfs transversely of a working face from left to right or vice versa and including cutting mechanism including a cutter chain circulating in opposite directions during cutting in opposite directions, of means for feeding said cutting mechanism to effect lateral cutting in either direction along a face including flexible feeding portions having free extremities and adapted to act alternatively during lateral cutting in opposite directions to advance and retard the opposite ends of said machine, and cooperating winding means of the same diameter rotatable by power at different points on said machine and at a plurality of speeds in the same direction and operable when feeding said machine laterally in opposite directions to draw in different portions as the advance portion while permitting lengthening of different portions as the receding portion.

92. A mining machine slidable on a mine bottom comprising a motor, cutting mechanism driven thereby including a circulating

cutter chain, and flexible feeding means for feeding said cutting mechanism into and laterally along a face including a plurality of flexible feeding portions each having a free extremity and connected by an intermediate portion, and means for drawing in either of said portions at a predetermined slow or cutting speed while said cutting mechanism rotates in the same direction including cooperating feed operating means and cooperating guiding means whereby upon reverse arrangement of said intermediate portion of said flexible means relative to said feed operating means the feed may be reversed at will while said feed operating means operates in the same direction.

93. A mining machine slidable on a mine bottom comprising a motor, cutting mechanism driven thereby including a circulating cutter chain, and flexible feeding means for feeding said cutting mechanism into and laterally along a face including an intermediate flexible portion and advance and receding portions each having a free extremity and each adapted to act on the opposite ends of the machine frame during lateral cutting, and means for drawing in either of said portions at a predetermined slow or cutting speed while said cutting mechanism rotates in the same direction including feed operating means and cooperating guiding means whereby upon reverse arrangement of said intermediate portion of said flexible means relative to said feed operating means the feed may be reversed at will while said feed operating means operates in the same direction.

94. A mining machine slidable on a mine bottom comprising a motor, cutting mechanism driven thereby including a circulating cutter chain, and flexible feeding means for feeding said cutting mechanism into and laterally along a face including a plurality of flexible feeding portions each having a free extremity and an intermediate portion connecting said portions, and means for drawing in either of said portions at a predetermined slow or cutting speed while said cutting mechanism rotates in the same direction presenting at either side of said machine frame a feed operating member rotatable on an axis transverse to the machine frame and cooperating guiding means whereby upon reverse arrangement of said intermediate portion of said flexible means relative to said feed operating means the feed may be reversed at will.

95. The combination with a mining machine, of a truck driving member, a motor, fast and slow speed reduction gearing for said truck driving member whose elements rotate on axes parallel to a line parallel to the axis of said truck driving member, and friction clutch mechanism interposed between said fast and slow speed reduction gearing and said member.

96. The combination with a mining machine slidable over a mine bottom, of a feed operating member adapted to cooperate directly with flexible feeding means, a truck driving member mounted on said machine for movement therewith during cutting, a motor, reduction gearing for driving said members at the same feeding speed, and friction clutch mechanism interposed between said gearing and one of said members, said gearing including a plurality of elements rotating on parallel axes and said last mentioned member rotating on an axis parallel to a line parallel to said axes. 70
- 10 97. The combination with a mining machine slidable over a mine bottom during cutting, of a truck driving member thereon movable therewith during cutting and adapted for connection with the running gear of a truck, a motor thereon, reduction gearing connected to said motor and comprising a plurality of intermeshing elements rotating on transverse axes, and friction clutch mechanism on said frame interposed between said gearing and said member and disposed coaxially with said member. 80
- 15 98. In combination with a mining machine slidable over a mine bottom during cutting, a truck driving member thereon, fast and slow speed reduction gearing thereon on said machine including elements rotating on a plurality of transversely extending axes, and a friction clutch mechanism interposed between the reduction gearing and said member and disposed coaxially with said member. 90
- 20 99. The combination with a mining machine, of a feed operating member adapted to cooperate with flexible feeding means in propelling the machine during cutting, a truck driving member adapted for operative connection by a flexible driving member in driving relation with the running gear of a truck, and rotatable on an axis parallel to a line parallel to that of said feed operating member, a motor, reduction gearing including a gear having a feeding speed, and means for connecting either member to said gear and one independently of the other. 100
- 25 100. The combination with a mining machine, of a feed operating member thereon adapted to cooperate directly with flexible feeding means, a truck driving member on the machine adapted for operative connection in driving relation to the running gear of a truck, a motor, plural predetermined speed reduction gearing between said motor and said feed operating member, and means for driving said truck driving member from said gearing at a plurality of predetermined speeds equal to those of said feed operating member. 110
- 30 101. The combination with a mining machine, of a feed operating shaft, a feed operating member rotatable therewith and adapted to cooperate directly with flexible feeding means, a truck driving member rotatable with said shaft and adapted for operative connection in driving relation to the running gear of a truck, a motor, reduction gearing therefor, and means for selectively driving said shaft from said gearing at any of a plurality of speeds. 115
- 35 102. The combination with a mining machine, of a feed operating member thereon adapted to cooperate directly with flexible feeding means, a truck driving member on the machine and adapted for operative connection in driving relation to the running gear of a truck, a motor, reduction mechanism therefor, and means for selectively connecting different elements of said reduction mechanism to either of said members to drive the latter at a plurality of like predetermined speeds. 120
- 40 103. The combination with a mining machine, of a feed operating member rotatable on a horizontal axis and adapted to cooperate directly with flexible feeding means thereon, a truck driving member on the machine, a motor, reduction mechanism therefor, and means including a friction clutch for selectively driving either of said members from said reduction mechanism at a plurality of different speeds. 125
- 45 104. The combination with a mining machine, of a feed operating member thereon adapted to cooperate directly with flexible feeding means, a truck driving member on the machine, said members rotating on axes parallel to the same line, a motor, reduction mechanism driven thereby, and means including a positive clutch and a friction clutch for selectively driving either of said members from said reduction mechanism at a plurality of predetermined speeds. 130
- 50 105. The combination with a mining machine, of feed driving mechanism including reduction gearing, a feed operating member adapted to cooperate directly with flexible feeding means, a truck driving member, said members rotating on axes parallel to the same straight line, and operative connections between said members and gearing including a plurality of clutches one operable to vary the speed of drive of either of said members. 135
- 55 106. The combination with a mining machine slidable on its bottom on a mine bottom, of a motor, reduction gearing driven thereby, a feed operating member adapted to cooperate directly with flexible feeding means, a coaxial truck driving member, and means including a plurality of clutches for selectively connecting either of said members to said reduction gearing for rotation thereby at different predetermined speeds. 140
- 60 107. The combination with a mining machine of a type slidable on a mine bottom during cutting and adapted to be mounted on a 145

truck for transport about a mine, of a plurality of drive trains on the machine comprising elements rotatable on parallel axes driven from a common source and producing rotation at different speeds, a truck driving member on said machine rotatable on an axis parallel to a line parallel to the axes of said trains, and means between said last mentioned elements for connecting said member to either train whereby it may be rotated at different predetermined speeds.

108. The combination with a mining machine slidable on its bottom on a mine bottom during cutting, of fast and slow speed drive trains thereon driven from a common source, feed operating and truck driving members on said machine rotatable on transverse axes, and means between said trains and members for connecting one of said members with either train and the other with one of said trains.

109. The combination with a mining machine slidable on its bottom on a mine bottom, of fast and slow speed drive trains thereon driven from a common source, feed operating and truck driving members on said machine rotatable on transverse axes, and means between said trains and members for connecting either of said members with either train.

110. The combination with a mining machine slidable on its bottom on a mine bottom, of a plurality of gear trains driven from a common source, laterally extending feed operating and truck driving members respectively driven thereby, said feed operating member being adapted to cooperate directly with flexible feeding means, and means for driving said truck driving member from either train.

111. The combination with a mining machine slidable on its bottom on a mine bottom, of a plurality of gear trains driven from a common source, one including a friction mechanism, coaxial feed operating and truck driving members respectively driven by said trains, said feed operating member being adapted to cooperate directly with flexible feeding means, and means for driving one of said members from either train.

112. The combination with a mining machine, of a plurality of fast and slow speed drive trains driven from a common source, coaxial feed and truck driving members connectible therewith, the former being adapted to cooperate directly with flexible feeding means, and means between said trains and members for driving either member through either train.

113. The combination with a mining machine, of a plurality of fast and slow speed drive trains driven from a common source, laterally extending flexible feeding means engaging and truck driving members connect-

ible with said trains, and means for driving one of said members through either train.

114. The combination with a mining machine, of a plurality of fast and slow speed drive trains driven from a common source, laterally extending flexible feeding means engaging and truck driving members connectible therewith, and means for driving either of said members through either train.

115. The combination with a mining machine slidable on its bottom on a mine bottom, of a plurality of trains of feeding mechanism thereon, a feed operating member adapted to be driven thereby and rotatable on a horizontally extending axis and cooperating directly with flexible feeding means, a truck driving member on said machine, means for driving said member through different trains, and a supplemental driving train for said member.

116. The combination with a mining machine slidable on a mine bottom during cutting and fed and guided by flexible machine feeding portions, of driving mechanism therefor including a constantly rotating gear, a feed operating member adapted to vary the length of one of said portions, a truck driving member rotatable on an axis parallel to a line parallel to that of said feed operating member, and means for selectively connecting a plurality of elements of said gearing to said feed operating member or to said truck driving member.

117. The combination with a mining machine slidable over a mine bottom and having cutting mechanism including a cutter bar, flexible feeding mechanism for feeding said machine laterally during cutting including a feed operating member, a cooperating flexible feeding member, means for driving said feed operating member at a cutting speed in one direction, and means whereby the direction of feed of said machine may be selectively reversed including a reversible driving motor adapted to drive said feed operating member reversely, stationary guiding means on said machine permitting reverse arrangement of said flexible feeding member to effect drawing in of different portions of the latter at the same speeds without reversing the motor, and operative connections between said feed operating member and motor whereby without reversing the motor the direction of rotation of said feed operating member may be reversed.

118. In a mining machine, in combination, a machine frame, cutting mechanism arranged at one end thereof, and feeding means therefor including a flexible feeding member and means on said frame adapted to cooperate with said flexible feeding member including a feed operating member adapted operatively to engage said flexible member during feeding, and pairs of idler guiding members arranged at opposite sides of said feed operating member and rotatable on

fixed axes at the opposite end of said frame from said cutting mechanism.

119. In a mining machine, a feed operating shaft, a feed operating member driven thereby and arranged coaxially therewith and adapted to cooperate directly with flexible feeding means, a plurality of driving members for said shaft concentric therewith, a sleeve on said shaft, means for connecting said sleeve to said shaft and disconnecting it therefrom, and means for selectively connecting said driving members to said sleeve.

120. In a mining machine, a feed operating shaft, a feed operating member driven thereby and arranged coaxially therewith and adapted to cooperate directly with flexible feeding means, a plurality of driving members concentric with said shaft and spaced apart thereon, a sleeve on said shaft, means for connecting said sleeve to said shaft or disconnecting it therefrom, and means for selectively connecting said driving members to said sleeve.

121. In a mining machine, a feed operating shaft, a plurality of drive members concentric therewith and spaced apart thereon, a sleeve on said shaft, means for connecting said sleeve to said shaft or disconnecting it therefrom, means for selectively connecting said driving members to said sleeve, and a truck driving member driven by said shaft.

122. In a mining machine, a feed operating shaft, a plurality of driving members concentric therewith and spaced apart thereon, a sleeve on said shaft, means for connecting said sleeve to said shaft or disconnecting it therefrom, means for selectively connecting said driving members to said sleeve, and feed operating and truck driving members driven by said shaft.

123. In a mining machine, a feed operating shaft, a plurality of driving members concentric therewith and spaced apart thereon, a sleeve on said shaft, means for connecting said sleeve to said shaft or disconnecting it therefrom, means for selectively connecting said driving members to said sleeve, and feed operating and truck driving members carried on the opposite ends of said shaft.

124. In a room and pillar mining machine, a feed operating member adapted to cooperate directly with flexible feeding means, a feed operating shaft, and driving means therefor including a plurality of driving members, a plurality of cooperating driving members driven thereby and disposed concentric with said shaft, and means for selectively connecting said concentric members and shaft, the connection of one of said members to said shaft producing a rotation of the latter at a rate for a transverse cutting speed, the connection of another of said members to said shaft producing rotation of the latter at a speed above the maximum for a cutting speed, and connection of another of said members producing rotation of said shaft at a still higher speed, and a truck driving member operatively connected to said shaft.

a cutting speed, and connection of another of said members producing rotation of said shaft at an intermediate speed.

125. In a room and pillar mining machine, a feed operating member adapted to cooperate directly with flexible feeding means, a feed operating shaft, and driving means therefor including a plurality of driving members, a plurality of cooperating driving members driven thereby and disposed concentric with said shaft, and means for selectively connecting said concentric members and shaft, the connection of one of said members to said shaft producing a rotation of the latter at a rate for a transverse cutting speed, the connection of another of said members to said shaft producing rotation of the latter at a speed above the maximum for a cutting speed, and connection of another of said members producing rotation of said shaft at a still higher speed.

126. In a room and pillar mining machine, a feed operating member adapted to cooperate directly with flexible feeding means, a feed operating shaft, and driving means therefor including a plurality of driving members, a plurality of cooperating driving members driven thereby and disposed concentric with said shaft, and means for selectively connecting said concentric members and shaft, the connection of one of said members to said shaft producing a rotation of the latter at a rate for a transverse cutting speed, the connection of another of said members to said shaft producing rotation of the latter at a speed above the maximum for a cutting speed, and connection of another of said members producing rotation of said shaft at a still higher speed.

127. In a room and pillar mining machine, a feed operating member adapted to cooperate directly with flexible feeding means, a feed operating shaft, and driving means therefor including a plurality of driving members, a plurality of cooperating driving members driven thereby and disposed concentric with said shaft, and means for selectively connecting said concentric members and shaft, the connection of one of said members to said shaft producing a rotation of the latter at a rate for a transverse cutting speed, the connection of another of said members to said shaft producing rotation of the latter at a speed above the maximum for a cutting speed, and connection of another of said members producing rotation of said shaft at a still higher speed, and a truck driving member operatively connected to said shaft.

128. The combination with a mining machine, of transversely disposed feed operating and truck driving members, said feed operating member being adapted to cooperate directly with flexible feeding means, and

controlling means therefor including coaxially disposed friction clutches and means for independently operating said friction clutches.

5 129. The combination with a mining machine, of coaxially disposed oppositely extending feed operating and truck driving members, driving means therefor including a pair of frictions disposed coaxially with said members, and means for controlling said frictions.

10 130. The combination with a mining machine, of a motor thereon, a truck driving member rotatable to effect transport from one working place to another, driving connections between said motor and said member, a feed operating member operative to effect feed during cutting, and driving connections between said connections and both of said members including a variable speed mechanism.

15 131. The combination with a mining machine adapted to be transported from place to place on a truck but to move relatively to the latter during cutting, of feeding mechanism for the machine operative to effect feed during cutting including a variable speed mechanism, a truck driving member rotatable to effect transport from one working place to another, means for selectively driving said member at different speeds through said variable speed mechanism, and supplemental means for driving said truck driving member at a different speed.

20 132. The combination with a mining machine adapted to be transported from place to place on a truck but to move relatively to the latter during cutting, of feeding mechanism comprising fast and slow feed trains, a feed operating member selectively connectible therewith and operative to effect feed during cutting, a truck driving member connectible with either train and rotatable to effect transport from one working place to another, and a supplemental driving train for rotating said truck driving member at a higher speed.

25 133. The combination with a mining machine adapted to be transported from place to place on a truck but to move relatively to the latter during cutting, of a motor thereon, a truck driving member rotatable to effect transport from one working place to another, driving connections between said motor and said member, a feed operating member operative to effect feed during cutting, and connections between said connections and said feed operating member including a plurality of drive trains and clutch mechanism controlling the connection thereof to said feed operating member and truck driving member.

30 134. The combination with a mining machine, of a motor thereon, a truck driving member rotatable to effect transport from one working place to another, driving connec-

tions between said motor and said member, a feed operating member operative to effect feed during cutting, and connections between said connections and said feed operating member including a plurality of drive trains and a plurality of clutch mechanisms controlling the connection thereof to said feed operating member and truck driving member.

70

35 135. The combination with a mining machine adapted to cut kerfs transversely of a working face from left to right or vice versa and having a frame and cutting mechanism including a cutter chain circulating in opposite directions during cutting in opposite directions, of feeding mechanism for propelling said cutting mechanism laterally across the face in either direction during cutting including flexible feeding means in either direction of feed having flexible advance and receding portions for respectively advancing and retarding the opposite ends of the frame, and winding means, the advance flexible feeding portion in either direction of cutting being wound in by winding means having a horizontal transverse axis of rotation and disposed on the then advancing side of the machine.

75

40 136. The combination with a mining machine adapted to cut kerfs transversely of a working face from left to right or vice versa and having a frame and projecting cutting mechanism including a cutter chain circulating in opposite directions during cutting in opposite directions, of feeding mechanism for propelling said cutting mechanism laterally across the face in either direction during cutting including flexible feeding means in either direction of feed having flexible advance and receding portions for respectively advancing and retarding the opposite ends of the frame, and winding means, the advance flexible feeding portion in either direction of cutting being wound in by winding means having a horizontal axis of rotation and disposed in advance of the central longitudinal vertical plane of the machine.

80

45 137. The combination with a mining machine adapted to cut kerfs transversely of a working face from left to right or vice versa and having a frame and cutting mechanism including a cutter chain circulating in opposite directions during cutting in opposite directions of feeding mechanism for propelling said cutting mechanism laterally across the face in either direction during cutting including flexible feeding means in either direction of feed having flexible advance and receding portions for respectively advancing and retarding the opposite ends of the frame, and winding means, the advance flexible feeding portion in either direction of cutting being wound in by winding means disposed in advance of the central longitudinal vertical plane of the machine.

90

50 138. The combination with a mining ma-

chine adapted to cut kerfs transversely of a working face from left to right or vice versa and having a frame and cutting mechanism including a cutter chain circulating in opposite directions during cutting in opposite directions and a motor operatively connected with said cutting mechanism and rotating in opposite directions to effect opposite circulation of said cutter chain, of feeding mechanism for propelling said cutting mechanism laterally across the face in either direction during cutting including flexible feeding means in either direction of feed having flexible advance and receding portions for respectively advancing and retarding the opposite ends of the frame, and winding means, the advance flexible feeding portion in either direction of cutting being wound in by winding means having a horizontal transverse axis of rotation and disposed on the then advancing side of the machine.

139. The combination with a mining machine adapted to cut kerfs transversely of a working face from left to right or vice versa and having a frame and cutting mechanism including a cutter chain circulating in opposite directions during cutting in opposite directions and a motor operatively connected with said cutting mechanism and rotating in opposite directions to effect opposite circulation of said cutter chain, of feeding mechanism for propelling said cutting mechanism laterally across the face in either direction during cutting including flexible feeding means in either direction of feed having flexible advance and receding portions for respectively advancing and retarding the opposite ends of the frame, and winding means, the advance flexible feeding portion in either direction of cutting being wound in by winding means having a horizontal axis of rotation and disposed in advance of the central longitudinal vertical plane of the machine.

140. The combination with a mining machine adapted to cut kerfs transversely of a working face from left to right or vice versa and having a frame and cutting mechanism including a cutter chain circulating in opposite directions and a motor operatively connected with said cutting mechanism and rotating in opposite directions to effect opposite circulation of said cutter chain, of feeding mechanism for propelling said cutting mechanism laterally across the face in either direction during cutting including flexible feeding means in either direction of feed having flexible advance and receding portions for respectively advancing and retarding the opposite ends of the frame, and winding means, the advance flexible feeding portion in either direction of cutting being wound in by winding means disposed in advance of the central longitudinal vertical plane of the machine.

141. The combination with a mining ma-

chine adapted to cut kerfs transversely of a working face from left to right and vice versa and having a frame and cutting mechanism including a cutter chain circulating in opposite directions during cutting in opposite directions, of feeding mechanism for propelling said cutting mechanism laterally across a face in either direction during cutting including flexible feeding means in either direction of feed having flexible advance and receding portions for respectively advancing and retarding the opposite ends of the frame, and winding means, the advance flexible feeding portion in opposite directions of cutting being wound in by winding means at opposite sides of the central longitudinal vertical plane of said frame.

142. The combination with a mining machine adapted to cut kerfs transversely of a working face from left to right or vice versa and having a frame and cutting mechanism including a cutter chain circulating in opposite directions during cutting in opposite directions, of feeding mechanism for propelling said cutting mechanism laterally across a face in either direction during cutting including flexible feeding means in either direction of feed having flexible advance and receding portions for respectively advancing and retarding the opposite ends of the frame, and winding means, the advance flexible feeding portion in opposite directions of cutting being wound in by winding means rotating on horizontal axes at opposite sides of the central longitudinal vertical plane of said frame.

143. The combination with a mining machine adapted to cut kerfs transversely of a working face from left to right or vice versa and having a frame and cutting mechanism including a cutter chain circulating in opposite directions during cutting in opposite directions, of feeding mechanism for propelling said cutting mechanism laterally across the face in either direction during cutting including flexible feeding means in either direction of feed having flexible advance and receding portions for respectively advancing and retarding the opposite ends of the frame, and winding means, the advance flexible feeding portion in opposite directions of cutting being wound in by winding means rotating on horizontal transverse axes at opposite sides of the central longitudinal vertical plane of said frame.

144. The combination with a mining machine adapted to cut kerfs transversely of a working face from left to right or vice versa and having a frame which rests upon and slides over the mine bottom during cutting, and cutting mechanism including a cutter chain circulating in opposite directions during cutting in opposite directions, and a motor operatively connected with said cutting.

mechanism and rotating in opposite directions to effect opposite circulation of said cutter chain, of feeding mechanism for summing said cutting mechanism into a working face and thereafter propelling said cutting mechanism laterally across the face in either direction during cutting including flexible feeding means having during summing at either rib a flexible portion extending between the side of the machine adjacent said rib and said rib, and winding means operating to shorten said portion, said portions during summing at different ribs being wound in by winding means at different sides of the central longitudinal vertical plane of said machine.

145. The combination with a mining machine adapted to cut kerfs transversely of a working face from left to right or vice versa and having a frame and cutting mechanism including a cutter chain circulating in opposite directions during cutting in opposite directions, of feeding mechanism for summing said cutting mechanism into a working face and thereafter propelling said cutting mechanism laterally across the face in either direction during cutting including flexible feeding means including during summing at either rib a flexible portion extending between the side of the machine adjacent said rib and said rib, and winding means operating to shorten said portion, said portions during summing at different ribs being drawn in by winding means at different sides of the central longitudinal vertical plane of said machine but in each case rotating on a horizontal axis.

146. The combination with a mining machine adapted to cut kerfs transversely of a working face from left to right or vice versa and having cutting mechanism including a cutter chain circulating in opposite directions during cutting in opposite directions, of feeding mechanism for summing said cutting mechanism into a working face and thereafter propelling said cutting mechanism laterally across the face in either direction during cutting including flexible feeding means including during summing at either rib a flexible portion extending between the side of the machine adjacent said rib and said rib, and winding means operating to shorten said portion, said portions during summing at different ribs being drawn in by winding means at different sides of the central longitudinal vertical plane of said machine but in each case rotating on a horizontal transverse axis.

147. The combination with a mining machine adapted to cut kerfs transversely of a working face from left to right or vice versa and having cutting mechanism including a cutter chain circulating in opposite directions during cutting in opposite directions and a motor operatively connected with said cutting mechanism and rotating in opposite directions to effect opposite circulation of said cutter chain, and a frame slidable upon a

mine bottom during cutting, of feeding mechanism for summing said cutting mechanism into a working face and thereafter propelling said cutting mechanism laterally across the face in either direction during cutting including flexible feeding means including during summing at either rib a flexible portion extending between the side of the machine adjacent said rib and said rib, and winding means operating to shorten said portion, said portions during summing at different ribs being wound in by winding means at different sides of the central longitudinal vertical plane of said machine.

148. The combination with a mining machine adapted to cut kerfs transversely of a working face from left to right or vice versa and having cutting mechanism including a cutter chain circulating in opposite directions during cutting in opposite directions and a motor operatively connected with said cutting mechanism and rotating in opposite directions to effect opposite circulation of said cutter chain, of feeding mechanism for summing said cutting mechanism into a working face and thereafter propelling said cutting mechanism laterally across the face in either direction during cutting including flexible feeding means having during summing at either rib a flexible portion extending between the side of the machine adjacent said rib and said rib, and winding means operating to shorten said portion, said portions during summing at different ribs being drawn in by winding means at different sides of the central longitudinal vertical plane of said machine but in each case rotating on a horizontal axis.

149. The combination with a mining machine adapted to cut kerfs transversely of a working face from left to right or vice versa and having cutting mechanism including a cutter chain circulating in opposite directions during cutting in opposite directions and a motor operatively connected with said cutting mechanism and rotating in opposite directions to effect opposite circulation of said cutter chain, of feeding mechanism for summing said cutting mechanism into a working face and thereafter propelling said cutting mechanism laterally across the face in either direction during cutting including flexible feeding means having during summing at either rib a flexible portion extending between the side of the machine adjacent said rib and said rib, and winding means operating to shorten said portion, said portions during summing at different ribs being drawn in by winding means at different sides of the central longitudinal vertical plane of said machine, but in each case rotating on a horizontal transverse axis.

150. In a mining machine, in combination, a motor, cutting mechanism actuated thereby, and feeding mechanism including feed

- operating means rotating on a horizontal axis and adapted to cooperate directly with flexible feeding means, and actuating means for said feed operating means including plural speed driving gearing comprising sets of intermeshing elements rotating on parallel axes certain of which are in alinement with the axis of rotation of said feed operating member, and means including a friction clutch 5 coaxial with said feed operating means and controlling said gearing.
151. In a mining machine, in combination, a motor, cutting mechanism actuated thereby, and feeding mechanism including feed 10 operating means rotating on a horizontal axis and adapted to cooperate directly with flexible feeding means, and actuating means for said feed operating means including plural speed driving gearing comprising sets of intermeshing elements rotating on parallel axes certain of which are in alinement with the axis of rotation of said feed operating member, and means including a plurality of friction clutches controlling drive by said 15 gearing, one of said friction clutches being coaxial with said feed operating means.
152. In a mining machine, in combination, a motor, cutting mechanism actuated thereby, and feeding mechanism including feed 20 operating means rotating on a horizontal axis and adapted to cooperate directly with flexible feeding means, and actuating means for said feed operating means including plural speed driving gearing comprising sets of intermeshing elements rotating on parallel axes certain of which are in alinement with the axis of rotation of said feed operating member, and means including a plurality of friction clutches disposed coaxially with said 25 feed operating means controlling drive by said gearing.
153. In a mining machine, a machine frame and means for effecting movement thereof over a mine bottom and also propelling the same, when mounted on a truck, about a mine, including a feed operating member adapted to cooperate directly with flexible feeding means, a truck driving member, and means for effecting rotation of said feed operating 30 member and of said truck driving member including a plurality of gear members coaxial with said feed operating member, and friction clutches coaxial with said gear members selectively loadable to cause the latter 35 alternatively to constitute driving elements for said feed operating and truck driving members.
154. In a mining machine, a machine frame and means for effecting movement thereof over a mine bottom and also propelling the same, when mounted on a truck, about a mine, including a feed operating member adapted to cooperate directly with flexible feeding 40 means, a truck driving member, and means for effecting rotation of said feed operating 45 member and of said truck driving member including a plurality of gear members coaxial with said feed operating member, and friction clutches coaxial with said gear members selectively loadable to cause the latter 50 alternatively to constitute driving elements for said feed operating and truck driving members.
155. In a mining machine, a machine frame and means for effecting movement thereof over a mine bottom and also propelling the same, when mounted on a truck, about a mine, including a feed operating member adapted to cooperate directly with flexible feeding means, a truck driving member coaxial with 55 said feed operating member, and means for effecting rotation of said feed operating member and of said truck driving member including a plurality of gear members coaxial with said members, and friction clutches coaxial with said gear members selectively loadable to cause the latter alternatively to constitute driving elements for said feed operating and truck driving members.
156. A mining machine comprising a machine frame, cutting mechanism including a projecting cutter bar, a motor for actuating said cutting mechanism, a feed operating member adapted to cooperate directly with flexible feeding means, and a truck driving member coaxial with said feed operating member, and means operated by said motor for driving said feed operating member and said truck driving member including plural speed gearing driven by said motor and including a plurality of gear elements coaxial with said feed operating member, and a plurality of gear elements meshing with said first mentioned gear elements and rotating on axes all of which are parallel to the axis of said feed operating member and a plurality of which lie in the same straight line.
157. A mining machine comprising a machine frame, cutting mechanism including a projecting cutter bar, a motor for actuating said cutting mechanism, a feed operating member adapted to cooperate directly with flexible feeding means, and a truck driving member coaxial with said feed operating member, and means operated by said motor for driving said feed operating member and said truck driving member including plural speed gearing driven by said motor and including a plurality of gear elements coaxial with said feed operating member, a plurality of gear elements meshing with said first mentioned gear elements and rotating on axes all of which are parallel to the axis of said feed operating member and a plurality of which lie in the same straight line, and clutch means coaxial with said feed operating and truck driving members determining the speed thereof.
158. A mining machine comprising a machine frame, cutting mechanism including

- a projecting cutter bar, a motor for actuating said cutting mechanism, a feed operating member adapted to cooperate directly with flexible feeding means, a truck driving member coaxial with said feed operating member, and means operated by said motor for driving said feed operating member and said truck driving member including plural speed gearing driven by said motor and including a plurality of gear elements coaxial with said feed operating member, a plurality of gear elements meshing with said first mentioned gear elements and rotating on axes all of which are parallel to the axis of said feed operating member and a plurality of which lie in the same straight line, and a plurality of friction clutches coaxial with said feed operating and truck driving members determining the speed thereof.
159. In a mining machine, a machine frame carrying cutting mechanism and actuating means therefor, and also means for propelling the same when mounted on a truck about a mine including a truck driving element on said frame and means on said frame for effecting rotation of said element including a plurality of gear members coaxial therewith and driving members meshing respectively with said gear members for rotating the same at different predetermined speeds, and means including a friction clutch disposed coaxially with said gear members loadable to cause the latter to constitute driving elements for said truck driving element.
160. In a mining machine, a machine frame carrying cutting mechanism and actuating means therefor, and also means for propelling the same when mounted on a truck about a mine including a truck driving element on said frame and means on said frame for effecting rotation of said element including a plurality of gear members coaxial therewith and driving members meshing respectively with said gear members for rotating the same at different predetermined speeds, and means including a plurality of selectively operable friction clutches disposed coaxially with said gear members loadable to cause the latter to constitute driving elements for said truck driving element.
161. In a mining machine, a frame carrying cutting mechanism and an actuating motor therefor, and adapted to be supported on a truck, and means adapted to propel said truck including an element carried by said frame, transmission means on said frame between said motor and said element comprising plural predetermined speed gearing comprising sets of intermeshing elements rotatable on parallel axes certain of which are coaxial with the axis of said element, and means including a friction clutch for controlling said gears.
162. In a mining machine, a frame carrying cutting mechanism and an actuating motor therefor, and adapted to be supported on a truck including an element carried by said frame, transmission means on said frame between said motor and said element comprising plural speed gearing comprising sets of intermeshing elements rotatable on parallel axes certain of which are coaxial with the axis of said element, and means including a plurality of friction clutches for controlling said gears.
163. In a machine of the nature described, the combination of cutting mechanism and a truck supporting the cutting mechanism, the truck comprising carrying wheels, axles on which said carrying wheels are mounted, a first shaft, gearing connecting said shaft with one of said axles, two gear members loosely surrounding the first shaft and rotating at different velocities, a second shaft, means for transmitting motion from said second shaft to one of the gear members, a third shaft, means for transmitting motion from the second shaft to the third shaft, a fourth shaft, means for transmitting motion from the third shaft to the fourth shaft, means for transmitting motion from the fourth shaft to the second of said gear members, and clutch mechanism for engaging either of said gear members to compel rotation of the first shaft, substantially as described.
164. In a machine of the nature described, the combination of cutting mechanism and a truck supporting the cutting mechanism, the truck comprising carrying wheels, axles on which said carrying wheels are mounted, a first shaft, gearing connecting said shaft to one of said axles, a gear member loosely surrounding said shaft, a second shaft, means between said second shaft and said gear member for rotating the latter, a second gear member also loosely surrounding the first shaft for rotation thereon, means between the first gear member and the second gear member for transmitting motion from the first gear member to the second gear member at a different velocity, and clutch mechanism on the first shaft for engaging either of said gear members to compel rotation of said shaft, substantially as described.
165. In a machine of the nature described, the combination of cutting mechanism and a truck supporting the cutting mechanism, the truck comprising carrying wheels, axles on which said carrying wheels are mounted, a first shaft, gearing connecting said shaft with one of said axles, two gear members loosely surrounding the first shaft, a second driven shaft, means for transmitting motion from said second shaft to one of said members, means comprising two speed reductions for transmitting motion from said member to the other of said members, and clutch mechanism for engaging either of said members to

compel the rotation of the first shaft, substantially as described.

166. In a mining machine, the combination with a feed operating member adapted to cooperate directly with a flexible feeding member, of mechanism for actuating the same comprising a motor shaft, a transmission shaft, a plurality of transmission elements for operatively connecting said shafts carried thereon, and alternatively operative clutches for connecting said elements respectively to one of said shafts.

167. In a mining machine, the combination with a feed operating member adapted to cooperate directly with a flexible feeding member, of mechanism for actuating the same comprising a motor shaft, a transmission shaft, variable speed gearing connecting said shafts, a countershaft operatively connected with said member, and variable speed gearing connecting said transmission shaft and countershaft.

168. In a mining machine, the combination with a feed operating member adapted to cooperate directly with a flexible feeding member in feeding said mining machine during cutting, of mechanism for actuating the same comprising a main transmission shaft, a countershaft operatively connected with said member, a plurality of transmission elements for operatively connecting said main transmission shaft and countershaft, and alternatively operative clutches on said countershaft for connecting said elements respectively with one of said shafts.

169. In a mining machine, the combination with flexible feeding mechanism including a feed operating member adapted to cooperate directly with a flexible feeding member of mechanism for actuating the same comprising a main transmission shaft, a countershaft operatively connected with said member, a plurality of transmission elements for operatively connecting said transmission shaft and countershaft, and alternatively operative friction clutches on said countershaft for connecting said elements respectively with one of said shafts.

170. The combination with a truck having propelling means, of a separable bottom cutting mining machine carried by said truck, said mining machine having a feed operating member adapted to cooperate directly with a flexible feeding member and mechanism for actuating said feed operating member comprising a main transmission shaft, a countershaft connected with said member, direct and speed reducing gearing operatively connecting said shafts, and truck propelling means including an element coaxial with and rotatable by one of said shafts.

171. In a mining machine, a driving motor having a horizontal armature shaft extending longitudinally of the machine and disposed in the central longitudinal vertical

plane of the latter, and feeding means driven by the adjacent end of said motor including a feed operating member adapted to cooperate with flexible feeding means, and a plural speed driving mechanism having a gear of each speed disposed coaxially with said feed operating member.

172. In a mining machine, a driving motor having a horizontal armature shaft extending longitudinally of the machine and disposed in the central longitudinal vertical plane of the latter, and feeding means driven by the adjacent end of said motor including a feed operating member adapted to cooperate with flexible feeding means, and a plural speed driving mechanism, the gears of said mechanism being all disposed on axes parallel to a line parallel with the axis of said feed operating member.

173. In a mining machine, a driving motor having a horizontal armature shaft extending longitudinally of the machine and disposed in the central longitudinal vertical plane of the latter, and feeding means driven by said motor including a feed operating member adapted to cooperate with flexible feeding means, and a plural speed driving mechanism therefor having a driving gear for each speed arranged coaxially with said feed operating member and fast and slow speed clutches for selectively connecting said gears in driving relation with said feed operating member.

174. In a mining machine, a driving motor having a horizontal armature shaft extending longitudinally of the machine and disposed in the central longitudinal vertical plane of the latter, and feeding means driven by said motor including a feed operating member adapted to cooperate with flexible feeding means, and a plural speed driving mechanism therefor having a driving gear for each speed and fast and slow speed clutches arranged coaxially with said feed operating member for selectively connecting said gears in driving relation with said feed operating member.

In testimony whereof I affix my signature.
MORRIS P. HOLMES.
